ATTORNEY.

UNITED STATES PATENT OFFICE.

JOHN T. WILKIN, OF CONNERSVILLE, INDIANA.

DESIGN FOR AN IMPELLER.

SPECIFICATION forming part of Design No. 29,762, dated December 6, 1898.

Application filed February 28, 1898. Serial No. 672,107. Term of patent 14 years.

To all whom it may concern:

Be it known that I, JOHN T. WILKIN, a citizen of the United States, residing at Connersville, county of Fayette, State of Indiana,
5 have invented and produced a new and original Design for Impellers of Rotary Blowers and Gas-Exhausters, of which the following is a specification.

Figure 1 is a perspective view thereof. Fig. 10 2 is an end elevation thereof.
The impeller is provided with two or more lobes 3 3, which are arranged symmetrically with respect to an axis 4. Each lobe 3 is provided with two faces 5 5, and between the 15 inner ends of the lobes the impeller is provided with a waist 6 or concave portion the

face of which is provided with a recess 7, which extends a portion only of the length of the waist, thus leaving at each end a short shoulder 8.

The essential feature of my design is the recess 7, formed in the waist and leaving the shoulders 8 at each end thereof.

I claim as my invention—

The design for an impeller substantially as 25 shown and described.

In testimony whereof I affix my signature in the presence of two witnesses.

JOHN T. WILKIN.

Witnesses:

HYATT L. FROST,
H. RILEY.
